(57) **CLAIM**

The ornamental design for a display screen or portion thereof with animated graphical user interface for passenger of an autonomous aircraft as shown and described.

DESCRIPTION

FIG. 1 is a first image of a first configuration of a display screen or portion thereof with animated graphical user interface for passenger of an autonomous aircraft according to our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is a eighteenth image thereof;

FIG. 19 is a nineteenth image thereof;

FIG. 20 is a twelfth image thereof; and,

FIG. 21 is an twenty-first image thereof.

(Continued)

The appearance of the animated graphical user interface transitions between the images shown in FIG. 1 through FIG. 21. The process or period in which one image transitions to another forms no part of the claimed design. The dot-dashed-line rectangle illustrates the perimeter of a portion of a display screen and forms no part of the claimed design.

The text shown in broken lines forms no part of the claimed design.
